DESIGN.

J. A. FLESCH.
SALES COUNTER.

No. 25,181

Patented Feb. 18, 1896.

UNITED STATES PATENT OFFICE.

JULIUS A. FLESCH, OF CHICAGO, ILLINOIS.

DESIGN FOR A SALES-COUNTER.

SPECIFICATION forming part of Design No. 25,181, dated February 18, 1896.

Application filed August 19, 1895. Serial No. 559,849. Term of patent 7 years.

To all whom it may concern:

Be it known that I, JULIUS A. FLESCH, a citizen of the United States, residing at Chicago, in the county of Cook and State of Illinois, 5 have invented and produced a new, useful, and original Shape or Design for Sales-Counters, of which the following is a full, clear, and exact specification, reference being had to the accompanying drawings, forming a part there-
10 of, and in which—

Figure 1 is a front elevation of a sales-counter embodying my design. Fig. 2 is an end elevation thereof; and Fig. 3 is a trans-
verse section taken on the line 3 3, Fig. 1.

15 The leading feature of my design consists of a sales-counter having the projecting portion A arranged at the upper front side of the counter and having the upwardly and rear-
wardly inclined top B.

20 The projection A is a box-like portion formed along the upper front side of the counter just below its surface or top board C, the inclined top B of the projection A being extended downwardly and outwardly from
25 the under side of the board C to the front vertical portion a of the projection A which is apparently supported by a horizontally-pro-
jecting piece a' which constitutes the lower side of the projection A and extends rear-
wardly to the front wall D of the counter. The rear wall of the projection or box-like portion A is constituted by a mirror E which is visible through the plate B constituting the inclined top of the box-like portion A.

30 When viewed from the front the upper side of the box-like portion A is apparently constructed of a number of plates B which are of

oblong form and separated at their ends by division strips or beads F, which extend downwardly from an overhanging bead c on the 40 front edge of the portion C to a continuous beading b extending along the upper edge of the portion a. This bead b, as also the portion a, is continued around the end of the counter, as shown at b' a'', respectively, in 45 Fig. 2, and the bead c is likewise continued around the end of the counter, as shown in such figure.

Arranged at intervals under the portion a' are a number of brackets or scrolls G which 50 apparently support the portion a' upon imitation pillars H formed on the front of the counter and extending upwardly from a horizontal panel I. Extending from the lower edge of one of these brackets G to the other is 55 a continuous bead or molding K, and arranged under this molding between each pair of the pillars is an oblong panel L and two smaller panels M, arranged one at each end of the panel L, the three panels being formed on the 60 front of the counter. On the end of the counter appears the imitation of a pillar or post N at each corner and between which is a panel O, while above this latter is an oblong panel P.

Having thus described my invention, what 65 I claim as new therein, and desire to secure by Letters Patent, is—

The new, useful and original shape or de-
sign for a sales-counter, substantially as here-
in shown and described.

JULIUS A. FLESCH.
